[57] CLAIM

The ornamental design for a dental pick, as shown and described.

DESCRIPTION

FIG. 1 is a perspective view of a dental pick showing my new design, the stippling of the central or shaft portion of the dental pick indicates a contrasting color from that of the end portion;

FIG. 2 is a side elevational view thereof, the other side elevational view being a mirror image of that shown;

FIG. 3 is a front elevational view thereof; and,

FIG. 4 is a rear elevational view thereof.

FIG. 1.***FIG. 2.******FIG. 3.******FIG. 4.***
